UNITED STATES PATENT OFFICE.

PHILIP J. KNAUFF, OF NEW YORK, N. Y.

SPRING-ATTACHING CLIP.

1,104,678.

Specification of Letters Patent. Patented July 21, 1914.

Application filed January 16, 1914. Serial No. 812,566.

To all whom it may concern:

Be it known that I, PHILIP J. KNAUFF, a citizen of the United States, residing at New York, in the county of New York and State of New York, have invented a new and useful Spring-Attaching Clip, of which the following is a specification.

My invention relates to certain improvements in attaching clips for springs and has for an object to provide a clip of simple construction which is adapted to easily and at the same time rigidly engage one convolution of the spring and to encircle the ratan or cane for the securing of the spring thereto.

15 A further object is to provide a spring attaching clip which is struck from a blank sheet of metal and which is bent to encircle or encompass the ratan and is provided with openings through which one end of the 20 spring coil is passed and having once been positioned therein will be rigidly retained in such relation.

With the foregoing and other objects in view which will appear as the description 25 proceeds, the invention resides in the combination and arrangement of parts and in the details of construction hereinafter described and claimed, it being understood that changes in the precise embodiment of the invention herein disclosed, can be made within 30 the scope of what is claimed, without departing from the spirit of the invention.

In the drawings accompanying this specification and forming a part thereof, the 35 preferable form of my invention is illustrated, in which:—

Figure 1 is a view in perspective of a ratan and spring coil with my improved spring attaching clip secured thereto. Fig. 2 is a 40 blank forming my improved spring attaching clip prior to the bending of the same for engaging the spring and cane. Fig. 3 is a cross sectional view taken on the line 3—3 of Fig. 1.

45 Referring to the drawings in which similar reference numerals designate corresponding parts throughout the several views, 4 is a ratan or cane and typifies the ordinary strip over which the canvas is drawn in a box 50 spring of the ordinary construction. A helical and spiral spring coil 5 is illustrated in Figs. 1 and 3 and is secured to the ratan or cane 4 by my improved spring attaching clip.

55 My improved spring attaching clip comprises in blank a body portion 6 which is provided with the slots 7 adjacent the ends

thereof and through which a convolution of the spring 5 is adapted to pass when the blank is bent into the form illustrated in Fig. 1. Extending at right angles to the longitudinal axis of the body portion 6 are the arms 8 between the outer extremities of which extends the cross member or rod 9. Located upon opposite sides of the body portion 6 are the fingers 10 which are spaced apart a distance less than the spacing of the arms 8 and are so positioned with respect to the latter that they will when bent toward the same extend therebetween so as to be capable of engaging the rod or cross member 9. The blank is preferably formed from a sheet of thin metal so that the body portion will be capable of bending along the longitudinal line 11. The clip is first bent upon the line 11 of the body portion so as to define the ledge 12 and the flange 13. The end of one convolution of the spring 5 is then passed through one of the openings 7 and out of the opposite opening and due to the fact that the line 11 along which the body portion is bent is substantially tangential to one side of the opening 7 the wire of which the spring is formed will contact with the under surface of the ledge 12 as illustrated in Fig. 1.

The ledge 12 is made of a width approximately equal to the diameter of the ratan or cane 4 so that the fingers 10 will extend at right angles to the ledge 12 and engage the cross member or bar 9 which is brought in such relation by reason of the arms 8 being circled around the cane 4. In order to facilitate the bending of the arms 8 and to further provide that the said arms and flange 13 will tightly and forcibly engage the cane 4, suitable openings 14 are provided in the extremities of the arms 8 and into which the end of a pair of pincers may be inserted or other device which will contact and engage the ledge 12 and the slot 14 so as to draw the same together, after which the fingers 10 may be bent around the cross bar 9 illustrated in Fig. 1 to rigidly hold the arms and flange in forced contact with the cane 4 as described.

Fig. 3 clearly illustrates the fact that the wire of the spring 5 extends to the remote side of the clip and so will be prevented from any lateral or longitudinal movement with respect thereto and at the same time will be prevented from passing from the openings or slots 7. The cross bar or member 9 allows the fingers 10 to engage the

same even though the cane or ratan be of uneven surface which is likely to occur, and even though the ratan be of decidedly uneven contour, the fingers will engage some 5 portion of the bar 9.

The improved clip may be used to secure the ratan to the under portion or bottom of a spring coil as illustrated in Fig. 1, although it is to be noted that in the ordinary use of 10 the device the ratan will be secured to the top of the coil such as would be obtained were the structure in Fig. 1 inverted.

Having thus fully described my invention, what I claim is:—

- 15 1. A spring attaching clip comprising a body portion bent along a longitudinal line to form a ledge and outstanding flange, arms carried by the said flange and carrying a cross bar which extends therebetween,
- 20 20 spaced fingers extending from the ledge adapted to engage the cross bar for securing the attaching clip to the rod-like member, and means for securing a spring to said clip.
- 25 2. A spring attaching clip comprising a body portion bent along a longitudinal line and defining a ledge and a flange extending therefrom, spaced arms extending from said flange and carrying a cross bar at their extremities, a plurality of spaced fingers projecting from the said ledge spaced apart a distance relatively less than the spacing of the arms, said fingers adapted to engage the cross bar and interlock therewith, the said flange provided at its upper extremity with 30 35 slots extending therethrough positioned ad-

jacent the ends thereof, said slots adapted to receive a convolution of a spring therein for the securing of the same thereto, the said flange and arms adapted to engage a rod-like member for the securing of the spring 40 thereto.

3. The combination with a rod-like member and a spring, of a clip comprising a body portion bent along a longitudinal line to define a ledge and perpendicular flange, 45 the said flange provided along its lower edge with curved arms, a cross rod extending between the extremities thereof and carried thereby, a plurality of spaced fingers located a distance apart relatively less than the 50 spacing of the said arms, said fingers projecting from the said ledge along the free edge thereof and adapted to interlock with and engage the cross bar which extends between the said fingers, said flange provided with slots extending therethrough located 55 near the ends and upper edge thereof, said slots adapted to receive a convolution of the said spring therethrough, said convolution extending beneath and in contact with the 60 said ledge and bearing against the said fingers.

In testimony that I claim the foregoing as my own, I have hereto affixed my signature in the presence of two witnesses.

PHILIP J. KNAUFF.
